CLAIM

The ornamental design of a display table for serving pizza and the like, as shown and described.

DESCRIPTION

FIG. 1 is a perspective view of a display table for serving pizza and the like showing my new design;

FIG. 2 is an end elevational view, the opposite end being a mirror image thereof;

FIG. 3 is a front elevational view thereof;

FIG. 4 is a rear elevational view thereof; and

FIG. 5 is a top plan view thereof.
